ATTORNEY.

UNITED STATES PATENT OFFICE.

EDWARD H. BLOSSOM, OF ST. JOHNSBURY, VERMONT, ASSIGNOR TO THE DUPONT MANUFACTURING COMPANY, OF SAME PLACE.

POWER-HAMMER.

SPECIFICATION forming part of Letters Patent No. 642,070, dated January 30, 1900.

Application filed February 26, 1898. Serial No. 671,871. (No model.)

To all whom it may concern:

Be it known that I, EDWARD H. BLOSSOM, a citizen of the United States, residing at St. Johnsbury, in the county of Caledonia and State of Vermont, have invented certain new and useful Improvements in Power-Hammers, of which the following is a specification.

My invention relates to improvements in power-hammers in which a vertically-reciprocating head operates in conjunction with a fixed anvil; and the objects of my improvement are, first, to provide springs or cushions by means of which the rigid parts of the frame are relieved of the shock or jar communicated thereto by the reciprocating head, and, second, to provide means for bringing the reciprocating parts to a condition of rest immediately after the work is done. I attain these objects by the mechanism illustrated in the accompanying drawings, in which—

Figure 1 is a perspective of the complete machine. Fig. 2 is a detail of spring-cushioned bolts holding front guide-plate. Fig. 3 is a vertical section showing brake applied. Fig. 4 is a vertical side view of same, and Fig. 5 is a vertical section showing brake not in use.

Similar letters refer to similar parts throughout the several views.

w is the frame of the machine, the lower part of which is designated by u in showing the anvil part of the machine.

t is the hammer-head or ram, held in suspension or operated by the spring-actuated mechanism (shown at x) and the crank wheel or disk d, revolvably supported on frame w, Fig. 1.

In Figs. 1 and 2, r is the front plate of guide-box q, in which the hammer runs. The front plate r is held in place on guide-box q by means of bolts e passing through ribs on guide-box q and the ribs s on frame w. Bolts e are provided with springs, as shown at f, Fig. 2. I make these springs of any spring material suitable for use in this class of machinery, but prefer flat steel springs or heavy coiled wire, the object of the spring being to provide an elastic cushion for the retaining-bolts of guide-plate r, whereby any abnormal jar or shock is absorbed without injury to the working parts of the machine.

It can readily be seen that the particular

form of spring is immaterial, and the spring is required to work but a very short distance, and while allowing the front guide-plate considerable flexibility has sufficient control of 55 said guide-plate to prevent it from getting out of alignment.

In Fig. 4, a is a tightening-pulley running on belt j j and is revolvably supported on a bell-crank lever b, pivoted at or near its middle 60 section on pin p, which is supported by a lug cast on frame w of the machine. Pin p projects through bell-crank lever b and into a recess in pulley u. p is flattened at its inner end, as shown at i, Figs. 3, 4, and 5. 65

b is a metal ring of a size a trifle smaller than the recess in pulley n, in which it is placed. This metal ring or brake is cut through at m, midway between the adjustable lugs h. The brake-ring has a boss at its lower 70 internal side, into which a pin from w is inserted that prevents the brake-ring from being turned with the pulley.

The end k of bell-crank lever b is connected to foot-treadle v by a rod. Depressing the 75 treadle v draws down the end k of bell-crank lever b and correspondingly swings the other end, on which is supported pulley a, through an arc of a circle, forcing pulley a against belt j, tightening it sufficiently to cause pulley u to revolve, carrying with it the shaft o, on which is keyed crank wheel or disk d, which operates the reciprocating parts of the machine.

Fig. 5 shows the parts in position with the 85 machine at work, in which it will be seen the flattened end i of pin p stands in a vertical position, allowing the brake-ring to spring together and not touch pulley u. The pin p has a weighted lever keyed on its outer end, 90 on which is an adjustable weight c, Fig. 1. The function of this weight is to raise the end of bell-crank lever b when the pressure on treadle v is removed, carrying tightener a back through an arc of a circle, releasing the 95 belt. At the same time it turns pin p until its larger diameter infringes on adjustable lugs h, forcing them apart and by them forcing the brake-ring b open at m, causing it to bear forcibly all around the inner surface of 100 pulley n. It will be seen that by means of the adjustable lugs h the brake can be so ad-

justed as to make it perfectly automatic— *i. e.*, the belt cannot be tightened without releasing the brake, and the brake will be applied on releasing or slackening the belt.

5 I am aware that spring-retained bolts have been used before my invention thereof, and therefore do not claim the invention broadly; but

What I do claim, and desire to secure by 10 Letters Patent, is—

In combination with a power-hammer and its operating mechanism, including a driving-belt and driving-pulley a divided spring brake-band, provided with internal lugs near 15 its point of division, and arranged to bear against the said pulley when these lugs are forced apart, a bell-crank lever having its

horizontal stem extended at one end, flattened and arranged between the said lugs to act thereon when partly turned, a tightening-pulley carried by the said bell-crank lever and arranged to bear against the said driving-belt, a counterbalance-weight attached to an arm of the said lever and operating to force the said pulley against the said belt and to turn 20 the said stem so as to allow the contraction of the said brake-band and the free rotation of the said driving-pulley substantially as set forth.

E. H. BLOSSOM.
